UNITED STATES PATENT OFFICE.

VENCESLAUS F. MIKOLASEK, OF LANKIN, NORTH DAKOTA.

LIGHTING AND IGNITION SYSTEM FOR AUTOMOBILES.

1,421,285.

Specification of Letters Patent. Patented June 27, 1922.

Application filed August 19, 1919. Serial No. 318,466.

To all whom it may concern:

Be it known that VENCESLAUS F. MIKOLASEK, citizen of the United States of America, residing at Lankin, in the county of 5 Walsh and State of North Dakota, has invented new and useful Improvements in Lighting and Ignition Systems for Automobiles, of which the following is a specification.

10 The object of the invention is to provide a combined lighting and ignition system for use in connection with automobiles and the like wherein there shall be a relatively broad range of elasticity or adaptability in the matter of the interchangeable use of magneto and battery currents, the arrangement being such as to provide for the charging of the battery by the generator or magneto while the ignition circuit is supplied by the latter 15 from the surplus or overflow of current produced by the generator or magneto and means such as a transformer or commutator hereinafter referred to as a rectifier, being arranged in such relation to the circuits including the battery, generator and lighting and 20 ignition circuits as to provide for interchangeably and reversely transforming the current from the generator to charge the batteries or from the batteries to supply the ignition circuit, according to whether the latter is to be operated directly by the generator 25 or indirectly by the batteries.

With these and related objects in view the invention consists in a construction, combination and relation of parts of which preferred embodiments are illustrated in the accompanying drawings, it being understood that minor changes in construction and arrangement may be resorted to within the 30 scope of the claims without departing from the principles involved.

In the drawings:

Figure 1 is a diagrammatic view of one form of the system showing the related rectifier and timing mechanisms in section.

Figure 2 is a similar view of a slightly modified system wherein a slightly different form of rectifier is included.

Figure 3 is a similar view of another modification employing a rectifier of the construction shown in Figure 1 but wherein there is included a double battery as in the form shown in Figure 2.

Figures 4 and 5 are still other modified forms showing different arrangements of the

circuits embodying the same principle as that indicated in the previous figures.

Figure 6 is a further modification of the rectifier wherein the timer is constructed as an element thereof to adapt this feature of 60 the system to be applied in lieu of the ordinary timer.

Figure 7 is a transverse sectional view of the rectifier on the plane indicated by the line 7—7 of Figure 6 and being of the same 65 construction as that shown in Figure 1.

It will be noted that for the advantages of the system to be attained to the fullest extent it is desirable that the timer 10, which

may be of the ordinary or any preferred construction, the rectifier 11 and the generator 12 or magneto should be operated in timed 70

relation or synchronism, and to this end the usual cam shaft 13 of the engine is employed as the driving element, motion being com- 75

municated therefrom by means of suitable gears such as the worm 14 and worm gear 15 to the spindle 16 of the timer. When the 80

arrangement is as indicated in Figure 1 (the same arrangement however, being illustrated in Figure 2) the spindle 16 carries a brush or 85

contact arm 17 adapted for periodic engagement with the spaced contacts 18 carried by a cap 19 capable of a movement concentric 90

with the spindle 16 so as to move the contacts 18 relative to the path of the brush arm 17 to either advance or retard the spark as in 95

the ordinary practice, connection with any suitable lever or foot pedal for this purpose being effected for example by means of the attachment indicated at 20. Connected by 100

means of binding screws 21 with the contacts 18 which for convenience may be termed the stationary contacts of the timer, are the conductors 22 leading to the spark plugs 23, through an intensifier 24 if desired. Also 105

connected with a binding post 25 at the center of the cap of the timer and engaged with a spring contact 26 bearing upon the hub of 110

the brush arm 17 which for convenience may be termed the movable contact of the timer, is a conductor 27 leading to the secondary 28 of the induction coil of which the primary 115

is shown at 29.

The above described conductors including a wire 30 leading from the primary of the induction coil to the switch 31 constitute what

shall be hereinafter referred to as the ignition circuit which further includes the primary and secondary coil grounds 32 and the 110

engine grounds 33 of which the operation is as in the ordinary practice and is well understood.

The rectifier is constructed in the general 5 form of a commutator wherein the rotary member, as shown in Figures 1, 6 and 7 consists of conductive rings 34 and 35 having intercurrently arranged extensions forming segments 34^a and 35^a arranged alternately in 10 an annular series and separated by insulation as shown at 36. This rotary member is carried by a spindle 37 connected by suitable gearing 38 and 39 with the spindle of the timer as shown in Figure 1, or with the cam 15 shaft 13 through such intermediate gearing as may be adapted to secure a synchronous movement of the elements, and said rotary member is arranged for convenience within a suitable housing 40. A brush contact 41 20 in engagement with one of the commutator rings, as for example that indicated at 35, is connected by a conductor 42 with the alternately effective switch points 43 and 44 for alternate engagement by the arm 45 of the 25 above mentioned switch 31. In the arrangement illustrated in Figure 1 the other commutator ring 34 is grounded as at 46.

Also engaged respectively with the contact segments 34^a and 35^a of the rings 34 30 and 35 are the brush contacts 46' and 47 from the former of which extends a conductor 48 through a switch box or cutout 49 to a switch point 50 which is within the range 35 of movement of an arm 51 of the above-mentioned switch 31, while from the other brush contact 47 extends a conductor 52 to one pole of the battery 53. From the opposite pole of said battery extends a conductor 54 through an ammeter 55^a and thence to 40 the arm 51 of the switch 31. From another switch point 56 for engagement by the arm 51 of the switch in its alternative adjustment extends a conductor 57 which extends to the brush contact 46 or as indicated makes connection at 58 with the conductor 48 extending from said contact.

The magneto or generator 12 is grounded as at 59 and is connected by conductor 60 50 with switch point 61 for engagement by the arm 45 of the switch 31 and therefore when the switch is moved in the direction indicated by the arrow located adjacent thereto the generator current passes from the switch point 61 through the arm 45 and conductor 59 to the primary coil 29 to energize the ignition circuit, and the surplus current, or that not absorbed by the ignition, passes to the switch point 43 through the conductor 42 to the commutator ring 35.

60 Referring particularly to Figures 6 and 7 it will be noted that the commutator brushes consist of small rollers 62 which being spring-actuated have a firm yet yielding contact with the elements of the commutator on relatively narrow lines so that the

spaces or zones of insulation between the segments of the rings may be made narrow to afford the maximum extent of conductive surface. The brush 41 which conveys the alternating current from the generator to the commutator is provided with a spring 63 acting upon the stem 64 of the bearing roller 62 while the contacts 46' and 47 which take off the direct current from the segments of the commutator rings are provided with 70 roller-supporting arms 65 yieldingly actuated by springs 66, each of said brushes 46' and 47 having its contact rollers spaced apart a sufficient distance to contact at the same time with segments of the same polarity while the rolls of the two brushes simultaneously make contact with segments of opposite polarities, and both sets of rolls being simultaneously in the neutral or insulated position with reference to the rotary 75 member of the commutator. This arrangement provides for maximum efficiency, and the direct currents of different polarities taken off respectively by the brushes 46' and 47 are conveyed to the battery to charge the 80 same, the course of the current being from the switch point 43 through the conductor 42 to the brush 41 and thence from the brush 46' through the conductor 48, and cutout 49 to switch point 50, through switch arm 51, 85 conductor 55, ammeter 55^a, conductor 54 to battery and then through conductor 52 and brush 47 and ring 34 to ground 46.

When the position of the switch 31 is reversed, as for the purpose of starting the engine on the batteries, by moving it in the opposite direction to that indicated by the arrow, the course of the current from the battery is through the conductor 54 and the ammeter, conductor 55 to switch arm 51, 100 switch point 56 and conductors 57 and 48 to the brush 46 and thence from the brush 47 and conductor 52 to the other pole of the battery, while from the brush 41 the alternating current, due to the action of the commutator traverses the conductor 42 to switch point 44 and thence through switch arm 45 and conductor 30 to the primary induction coil to energize the ignition circuit.

The above described reversible circuit including the battery and consisting essentially of the connections between the A. C. brush 41 and the switch points 43 and 44, the connections between one of the D. C. brushes (46' and 47) and one pole of the 110 battery and between the other D. C. brush and the other pole of the battery, and in which is arranged the switch by which the directions of the currents with reference to the commutator are reversed, may be and hereinafter is termed the battery circuit.

In addition to the foregoing there is illustrated what is ordinarily termed a lighting circuit 67 which includes the battery and consists of a conductor 68 connected for 115

convenience with the conductor 54 leading to one pole of the battery, and a conductor 69 leading from the other pole of the battery through the conductor 52 to which it is connected, and in this lighting circuit there may be arranged the headlights 70, search-light 71, tail-light 72, bell 73, horn 74 or any equivalents thereof controlled by the switches 75 which are ordinarily arranged within 10 easy reach of the operator of the car.

In the modified form of the invention which is illustrated in Figure 2 the lead 76 from the generator 77 is connected with the switch point 78 so that when the arm 15 79 of the switch 31^a is in contact therewith the current will pass through the latter to the bridge 80, and while part of it will flow through the conductor 81 to the primary 82 of the induction coil, the balance will pass 20 from the bridge through the arm 83 of the switch to the point 84 and thence through conductor 85 to an intermediate pole of the double battery 86 of which the other poles are connected by conductors 87 and 88 respectively 25 to the brush contacts 89 and 90 for alternate contact with the segments 91 of the commutator disk 92. In this instance only a single disk is employed, with insulating elements 93 interposed between 30 the segments for engagement by one contact when the other is in engagement with a conductive segment, as indicated in the drawing, the disk being revolubly mounted as in the form illustrated in Figure 1 by 35 means of a spindle or shaft 94, and being grounded as indicated at 95.

When the position of the switch 31^a is reversed or moved in the opposite direction to the arrow the battery is thrown into the 40 circuit with the primary of the induction coil, the course of the current being from the remote poles of the battery alternately through the conductors 87 and 88 and brushes 89 and 90 and the segments 91 to 45 ground and thence through primary of the induction coil, conductor 81, bridge wire 80, switch arm 83, switch point 95' and conductor 85 to the intermediate pole of the battery, the magneto or generator being cut 50 out and commutator acting as a transformer to change the direct current of the battery into an alternating current in the induction coil.

In the arrangement illustrated in Figure 55 3 there is employed a double battery 96 similar to that indicated in Figure 2 with a corresponding connection of the generator 97 therewith through a lead 98, switch point 99, switch arm 100, bridge wire 101, and 60 conductor 102 to the primary 103 of the induction coil. In this form of the invention the ignition circuit 104 is similar to that previously described as also is the lighting circuit indicated at 105. The rectifier 65 used in this connection partakes of the

characteristics of both that shown in Figure 1 and detailed in Figures 6 and 7, and that shown in Figure 2 previously described, in that while its rotary member consists of two rings 106 and 107 having alternately 70 disposed or intercurrent conductive segments 106^a and 107^a separated by insulation 108, cooperating with contacts 109 and 110 which operate alternately with reference to each other and also with segments of different 75 polarities, the zones of insulation 108 between the conductive segments of the opposed disks being of sufficient width to insulate one contact while the other is in operation, both rings or disks 106 and 107 are 80 grounded as shown respectively at 111 and 112. From the bridge 101 through which the magneto current passes to the induction coil 103, the surplus passes through switch arm 113 to point 114 and thence through 85 conductor 115 to the intermediate pole of the battery or the inner poles of the double battery as will be the effect of such an arrangement. From the outer poles or terminals of the battery members extend the conductors 116 and 117 respectively to contacts 109 and 110.

It will be obvious that by reversing the switch or moving it in the opposite direction to that indicated by the arrow, the generator or magneto will be cut out as heretofore explained with reference to the other forms of the invention and the current will then pass from the intermediate pole of the battery through the conductor 115 and 100 switch point 118, switch arm 113, bridge 101, conductor 102, and primary coil 103 to ground 119 and from ground to commutator rings 106 and 107 and segments 106^a and 107^a alternately through contacts 109 105 and 110 and conductors 116 and 117 to the remote terminals of the battery.

In the forms illustrated in Figures 4 and 5 still other modifications serving to secure the same results are illustrated as, for example, in Figure 4, the lead 120 of the generator 121 passes to the intermediate point of the battery structure 122 while from the extremities thereof extend conductors 123 and 124 to the brushes 125 and 126 which contact with rings 127 and 128 having intercurrent conductive segments 127^a and 128^a, separated by insulation 129, and for contact with segments alternately is arranged the brush 130 which is grounded as shown 120 at 131. In the form of Figure 5 where a single battery element 132 is shown the lead 133 from the generator 134 extends to a brush 135 in contact with the ring 136 of the commutator while the other ring 137 is 125 grounded as shown at 138. These rings are provided as in the previous form with intercurrent conductive segments 136^a and 137^a with which cooperate in simultaneous engagement the contacts 139 and 140 which 130

are connected by conductors 141 and 142 respectively with the opposite poles of the battery.

The modification illustrated in Figures 6 and 7 refer solely to the commutator or rectifier in its relation to the timer and its mounting upon the frame of the machine, in that there is employed a plate 143 adapted to be substituted for the timer ordinarily employed and is provided with attaching arms 144 to serve as means of attachment, and this plate is provided with a sleeve 145 to form a mounting for the spindle 146 geared as shown at 147 and 148 to the cam shaft 149. Keyed to the shaft is a sleeve or collar 151, and keyed upon the exterior surface of the latter is an insulating ring 152 which forms a part of the insulator serving to separate the conductive segments of the commutator rings. In this form of the device the brush arm 153 carrying the movable contact of the timer is attached to the spindle 146, and the rotary spark adjusting cap 154 by which the spark is advanced or retarded and which carries the contacts 155 is held in place by the engagement of curved spring fingers 156 with a rim or flange 157.

What is claimed is:

1. An ignition system having an alternating current generator, an ignition circuit, a battery, a transformer having one set of terminals included in the ignition circuit, a battery circuit including the other set of terminals of the transformer, and means for selectively including the generator in the ignition circuit.

2. An ignition system having an alternating current generator, an ignition circuit controlled by an induction coil, a battery, a transformer having one set of terminals included in the ignition circuit, a battery circuit including the other set of transformer terminals and the battery, and means for including the generator with the primary of the induction coil in the ignition circuit and with the transformer.

3. The combination with a rotary member operating in timed relation with the explosions of an internal combustion engine, of an ignition system having a commutator of

which the rotary element having one set of terminals is operatively connected to said member for synchronous movement therewith, an ignition circuit including the one set of commutator terminals, a battery having a circuit including the other set of commutator terminals, an alternating current generator, and a switch for connecting the generator directly with the primary induction coil element of the ignition circuit and with the first-named set of terminals of the commutator.

4. The combination with a timed rotary member of an explosion engine, of an ignition system having a commutator of which the rotary element is geared to said member for synchronous movement therewith, a battery having a circuit including one set of terminals of the commutator, an ignition circuit including the other set of terminals, and a generator for selective connection with said second-named set of terminals of the commutator and with the ignition circuit.

5. An ignition system having a commutator, a battery having its circuit arranged to include one set of terminals of the commutator, an alternating current generator connected to and an ignition circuit including the other set of terminals of the commutator, said ignition circuit being included in the battery circuit through the commutator when the generator is disconnected from said commutator.

6. An ignition system having a commutator, a battery having its circuit arranged to include one set of terminals of the commutator, an ignition circuit having an induction coil of which the primary is included with the other set of terminals of the commutator, an alternating current generator, and a switch for cutting the generator into and out of the ignition circuit and maintaining in both positions a closed condition of said ignition and battery circuits through the respective sets of terminals of the commutator.

In testimony whereof he affixes his signature.

VENCESLAUS F. MIKOLASEK.
